(57) **CLAIM**

The ornamental design for a hands free car adapter, as shown and described.

DESCRIPTION

FIG. 1 is an isometric rear view of the present invention; FIG. 2 is an isometric lower front view of the present invention;

FIG. 3 is a rear view of the present invention;

FIG. 4 is a front view of the present invention;

FIG. 5 is a right view of the present invention;

FIG. 6 is a left view of the present invention; and,

FIG. 7 is a top view of the present invention.

The broken lines throughout the drawing figures are included for the purpose of illustrating environmental structure only and form no part of the claimed design.
